(57) **CLAIM**

The ornamental design for a pen-style pocket screwdriver with work area illuminator, as shown and described.

DESCRIPTION

FIG. 1 is a bottom perspective view of a pen-style pocket screwdriver with work area illuminator, showing my new design;

FIG. 2 is a front view thereof;

FIG. 3 is rear view thereof;

FIG. 4 is a left side view thereof;

FIG. 5 is a right side view thereof;

FIG. 6 is a top view thereof;

FIG. 7 is a bottom view thereof; and,

FIG. 8 is a front view thereof illustrating a tool being retained by the pen-style pocket screwdriver with work area illuminator. The illumination and tool are shown in broken lines as environment and form no part of the claim.
